UNITED STATES PATENT OFFICE.

CHARLES W. DAKE, OF GRAND RAPIDS, MICHIGAN.

ELASTIC-FLUID TURBINE.

No. 845,059.

Specification of Letters Patent.

Patented Feb. 26, 1907.

Application filed March 22, 1906. Serial No. 307,457.

To all whom it may concern:

Be it known that I, CHARLES W. DAKE, a citizen of the United States, residing at Grand Rapids, in the county of Kent and State of Michigan, have invented certain new and useful Improvements in Elastic-Fluid Turbines, of which the following is a specification.

This invention relates to improvements in elastic-fluid turbines, and it relates more particularly to improvements in the buckets, and particularly to buckets of the recurved U-shape type. As these buckets are ordinarily constructed and arranged at an angle to the face of the turbine disk or wheel or at an angle to the periphery thereof, the fluid travels different distances from the nozzle before it develops the energy of its impact and reaction upon the bottom of the bucket. The result has been that buckets are made ordinarily of quite narrow dimensions, where of course it is obvious that if they were made of larger dimensions they could be made with greater facility and there would be less energy consumed in friction on the separating-walls.

The objects of this invention are, first, to provide an improved form of recurved bucket in which the power developed from the impact of the fluid is done at a substantially uniform distance from the mouth of the nozzle, consequently enabling the utilization of the jet of elastic fluid to the best possible advantage; second, to provide a form of bucket which will enable the utilization of the face or surface of the turbine-disk with a minimum number of separate and distinct buckets.

Further objects and objects relating to the details of construction will appear from the detailed description to follow.

I accomplish the object of my invention by the devices and means described in the following specification.

The invention is clearly defined and pointed out in the claims.

The portions of a steam-turbine which embody the features of my invention are clearly illustrated in the accompanying drawings,

50 forming a part of this specification, in which—

Figure 1 is a detail sectional view through a row of buckets with a nozzle in position taken on a line corresponding to line Z Z of Fig. 2. Fig. 2 is a plan view of buckets looking at the face of same, the nozzle being omitted. Fig. 3 is a detailed oblique sectional

view taken on a line X X of Fig. 1. Fig. 4 is a detailed sectional view of a slight modification of the buckets, taken on a line corresponding to line Z Z of Fig. 2, the U-shaped buckets being shown with walls curved in cross-section. Fig. 5 is a detailed view of the ordinary form of U-shaped recurved bucket, taken on a line corresponding to line Z Z of Fig. 2.

In the drawings similar numerals of reference refer to similar parts throughout the several views.

I show a section of a turbine-wheel or disk 1, with the recurved buckets with the oblique nozzle 2 leading from the nozzle-bowl 3 to deliver elastic fluid into the said buckets.

My improved recurved buckets are indicated by the numerals 4, 5, and 6, which are arranged in a stepped relation to each other, owing to their inclination, the inner curved walls 7, 8, and 9 being arranged somewhat like a flight of steps in relation to each other. The complete series are separated from each other by the separating-walls 10, which walls have circular notches at the center for convenience in machining out the steps by a rotary cutter or milling-tool.

The dotted line 11, Fig. 1, shows the position that the ordinary recurved bucket would take in the disk, and it will be observed that the disk would require to be considerably thicker, and it will be observed that the depth of the bucket would vary considerably, so that the jet of steam delivered from the nozzle would have a comparatively short distance to travel to react on the bucket when the bucket first came into work and would have a long distance to travel as it was leaving the nozzle.

The exact form of the usual recurved bucket appears clearly in Fig. 5, the bucket being indicated by 4', the bottom of same by 7', and the general form of this bucket, if it was attempted to arrange it in a thinner disk, is indicated by the dotted lines S S. A bucket of that shape would be very ineffectual, as much of the energy would be consumed in the friction and pressure on the opposite walls.

With the particular form of that I have illustrated it will be seen that the elastic fluid travels substantially the same distance no matter what the position of the bucket is in passing the nozzle, and therefore the nozzle can be adjusted and regulated at just the proper distance to secure the best results.

While I prefer the form of buckets which I have illustrated in Fig. 1, I am aware that the stepped wall of the bucket can be modified, as appears in Fig. 4, although there is considerable loss of energy in this modification. The buckets 4", 5", and 6" have the curved walls 7", 8", and 9" curved in cross-section, respectively, which would result in considerable loss of energy on account of the 5 said peculiar curved cross-section; but this would be a great advance over the usual form of buckets, as illustrated in Fig. 5.

If narrow buckets were made corresponding to the thickness of the various steps 4, 5, and 6 of my improved bucket, it is clear that a great amount of energy would be consumed by friction on the dividing-walls, which would not result in the development of energy. Therefore the advantage of the particular arrangement I have shown, which secures the proportionment and arrangement and advantages that would otherwise result from the comparatively narrow buckets, is obtained without the objectionable loss due 10 to friction on division-walls.

I show this structure in the form which I prefer; but I desire to remark that in place of machining the buckets in the disk into an integral construction the buckets can be made 15 in detached pieces and attached or could be made up in separate parts built on the disk. I have not illustrated these other forms, preferring merely to illustrate the form of construction preferred.

Having thus described my invention, what I claim as new, and desire to secure by Letters Patent, is—

1. The combination of a turbine disk or wheel with buckets of the U-shaped recurved type, formed in steps, the steps being similar and arranged side by side in substantially parallel relation; and a nozzle delivering to the said buckets.

2. A turbine disk or wheel with buckets of the U-shaped recurved type formed of parallel steps of similar depth to receive impact at substantially the same distance from the source of supply.

3. A turbine disk or wheel with buckets of the U-shaped recurved type formed of steps of similar depth to receive impact at substantially the same distance from the source of supply.

4. A turbine disk or wheel with buckets of the U-shaped recurved type whose curved walls are formed of steps of approximately similar radius.

5. A turbine disk or wheel with buckets of the U-shaped recurved type whose curved wall is formed of steps.

In witness whereof I have hereunto set my hand and seal in the presence of two witnesses.

CHARLES W. DAKE. [L. s.]
